(57) **CLAIM**

The ornamental design for a light fixture, as shown and described.

DESCRIPTION

FIG. 1 is a top view of a light fixture or similar article showing my new design;

FIG. 2 is a side view thereof, the opposing side view being a mirror image, with the broken line showing for illustrative purposes only and forming no part of the claimed design;

FIG. 3 is a bottom view thereof;

FIG. 4 is an end view thereof taken along the line 4—4 in FIG. 1;

FIG. 5 is an end view thereof taken along the line 5—5 in FIG. 1; and,

FIG. 6 is a perspective view thereof.
